BRAIDED ARTICLE

Peter Horace Boivin, Granby, Quebec, Canada

Application July 6, 1936, Serial No. 88,934

1 Claim. (Cl. 96—27)

This invention relates to braided articles and mechanism for producing the same.

It is well known that a loosely braided fabric possesses great crease and wrinkle resisting characteristics and consequently such a fabric is well suited for the manufacture of neckties. Up to the present time, however, no convenient or practical method has been proposed for producing articles of this type from such fabrics.

10 An object of the invention is to produce neckwear or like shaped articles from a wholly braided flat fabric. Another object is to produce such a fabric in a continuous length having portions of varying cross-section formed by alternately loosely and tightly braiding the same. A further object is to provide a simple mechanism for automatically and alternately varying the speed of the take-up rolls of a braiding machine whereby the fabric produced thereby will be alternately loosely and tightly braided, which mechanism may be readily applied to braiding machines now in use.

The invention will be described with reference to the accompanying drawing, in which,

25 Figure 1 is a side elevation of a mechanism in accordance with the invention,

Figure 2 is a front elevation of the mechanism shown in Figure 1, and

30 Figure 3 is a plan of a fabric produced by the mechanism shown.

In the drawing, 1 is the usual driven upright shaft for driving the horizontal shaft 2 of the take-up rolls 3 of a flat braiding machine. Instead of the usual single set of gearing between the 35 shafts 1 and 2, two sets are provided each arranged to be actuated by a worm 4 on shaft 1, which is provided with a universal joint 5 whereby the worm 4 may be moved into engagement with one or other of two worm wheels 6 and 40 7 adjacently mounted in framework 8. Worm wheel 6 is carried by a shaft 9 on which is mounted a gear 10 meshing with a relatively small gear 11 carried by shaft 2 of the take-up rolls. Worm wheel 7 is carried by a shaft 12 on which 45 is mounted a gear 13 meshing with a gear 14 rotatively carried by a shaft 15, gear 14 having meshing engagement with a relatively large gear 16 carried by shaft 2. Thus driving of shaft 2 through one set of gearing by means of large 50 gear 16 will be at a smaller speed than through the other set of gearing by means of small gear 11.

55 Means are provided for automatically and alternately placing worm 4 in mesh with worm wheels 6 and 7 and comprises an actuating rod 17 connected to shaft 1 and adapted to be actuated by

a lever 18 which bears upon a revolving chain 19 mounted on a fixed pulley 20 carried by a shaft 21 mounted in a frame member 22 and a floating pulley 23 carried by a bar 24 resiliently secured to the framework by means of a spring 25. Chain 19 is formed with a relatively long small link section A and a relatively short large link section B constituting a cam surface. A spring 26 connecting lever 18 with the frame 8 normally urges the actuating rod 17 to the right, as shown 10 in Figure 1, whereby when the lever 18 is in engagement with the small link section A of chain 19, the worm 4 will be in mesh with worm wheel 7, but when the large link section B engages the lever 18, it will be forced to the left to 15 move worm 4 into mesh with worm wheel 6.

Means for revolving chain 19 in accordance with the speed of shaft 1 comprises a ratchet wheel 27 mounted on shaft 21 and adapted to be actuated by a ratchet bar 28 eccentrically mounted 20 for reciprocal motion on a worm wheel 29 driven by a worm 30 on shaft 1. A spring 31 urges the bar 28 into engagement with the ratchet wheel 27.

The fabric which is led from the machine under 25 tension by means of the take-off rolls 3, is indicated at 32, and it will be readily appreciated that, when at intervals the speed of the rolls is increased and a greater "pull" exerted on the fabric, a more tightly braided section of 30 fabric having a greater number of yarn twists or turns to the inch will be formed during such intervals. Thus, as the fabric emerges from the rolls and the tension thereon is released, the 35 loosely braided sections will widen out but the tightly braided sections, being composed of a solid compact fabric, will retain their narrow cross-section. Therefore, with the mechanism described a fabric will be produced, such as is shown in Figure 3, having alternate wide loosely 40 braided sections 33 and narrow tightly braided sections 34, the sections 33 being of a greater length than the sections 34. It will be observed that the lengths of the sections 33 and 34, as well as the widths thereof, may be varied at will 45 by adjusting the chain 19 as to number and size of links, thus increasing or decreasing the frequency and extent of movement effected by the cam surface.

Any desired pattern may be incorporated in 50 the fabric during the braiding operation. It has been observed that a fabric especially suitable for the production of neckties having crease-resisting characteristics may be produced from an ordinary crepe twist yarn and that a rayon or 55

silk crepe yarn of contrasting color may be employed in conjunction therewith to form the desired pattern.

After formation of the fabric, the individual neckties are produced by severing the same at a suitable point intermediate the ends of the wide sections 33, and, if necessary, the individual articles may be provided with rows of stitching along the sides and ends thereof to more firmly 5 consolidate the shape thereof and to prevent ravelling.

I claim:

A necktie comprising a flat one-ply fabric of braided crepe yarn, the crepe yarn of the end portions of said fabric being relatively loosely braided to form non-creasing tie sections and the yarn in the intervening portion being tightly braided to form a relatively inextensible neck band portion adapted to slip easily through a collar. 5
